GEORGE L. BLANCHARD, OF MONTGOMERY, ALABAMA, ASSIGNOR TO BLANCHARD
DELINTER CO. OF MONTGOMERY, ALABAMA, A CORPORATION OF ALABAMA.

FLOAT FOR LINTERS.

1,122,360.

Specification of Letters Patent. Patented Dec. 29, 1914.

Application filed December 1, 1913. Serial No. 804,045.

To all whom it may concern:

Be it known that I, GEORGE L. BLANCHARD, a citizen of the United States, residing at Montgomery, in the county of Montgomery and State of Alabama, have invented certain new and useful Improvements in Floats for Linters; and I do hereby declare the following to be a full, clear, and exact description of the invention, such as will enable others skilled in the art to which it appertains to make and use the same.

The present invention relates to floats for linters for delinting cotton seed and has for its purpose to provide an arrangement whereby the float greatly assists the linter machine in removing the lint from the seed to the end of greater recovery of lint, and obtaining a larger amount of oil from the seed.

A further purpose of the invention is to construct a delinter float wherein the several parts thereof are simply constructed and easily assembled, or dis-assembled, and which may be readily installed in any linting machine without requiring any alteration in its structure.

The invention as disclosed herein is proposed as an improvement over that type of delinter float disclosed in my U. S. Patents, Nos. 947367 and 1015724, dated January 25, 1910 and January 23, 1912, respectively.

In the accompanying drawings forming a part of this application, and in which similar reference symbols indicate corresponding parts in the several views:—Figure 1 is a top plan view, with parts broken away and shown in section, of a linter; Fig. 1^a is a transverse sectional view of the float taken on the line 1—1 of Fig. 1. Fig. 2 is a longitudinal sectional view of the float with parts removed for clearness; Fig. 2^a is a transverse sectional view taken on the line 2—2 of Fig. 1; and Fig. 3 is a transverse sectional view taken on the line 3—3 of Fig. 2.

Referring to the construction in further detail, 1 designates the linter casing or roll box, having the usual saws 2 arranged to perform their ordinary functions.

The float consists of a plurality of cylindrical sections 3 composed of emery, or other abrasive substance, and which are co-axially assembled to provide a cylinder having a corrugated working surface. The cylinder portions between the several corrugations 4 have cylindrical extensions which, when the several cylinder sections are as-

sembled, provide abrasive shoulders 5, the purpose of which will be described hereinafter.

The several cylindrical sections of the abrasive cylinder are mounted on a shaft 6 of polygonal or circular design in cross section, and the means for securing the several cylinder sections consists of a plurality of co-axially-assembled bushings 7 that are mounted directly on the shaft 6, and at either end said bushings are secured through the medium of a pair of right and left threaded nuts 8 and 9, respectively. Said nuts 8 and 9 are mounted on the extreme ends of the shaft 6 within the casing 1, as shown clearly in Fig. 1.

Each bushing 7 is constructed with an annular end flanges 10 and 11, and said flanges are provided, respectively, with dowel pins 12 and corresponding recesses 13, adapted to have inter-engagement for locking the several axially-assembled bushings against relative angular movement. A pair of wings or projections 14 is formed on diametrically opposite sides of each bushing, and have for their purpose to engage within the abrasive cylinder sections and securely mount the latter on said bushing for obvious reasons. It will be understood, of course, that said projections or wings 14 are set within their respective cylinder sections during the period of formation or molding of the latter.

A reinforcing, endless welded ring 15 is located in each of the cylinder sections and provides a reinforcing element to prevent breakage of the wheel when the same is subjected to excessive wear or strain.

The several cylinder sections 3 are secured to their respective bushings through the medium of a binding filler 16 which is located within the space provided between the bushings, bushing end flanges and the inner peripheries of the cylinder sections.

The binder is composed preferably of sulfur combined with rubber, or other similar substance, which will give it a very hard and tenacious body, to the end of overcoming the brittleness of the sulfur.

A cage surrounds the abrasive cylinder 105 and consists of four bars 17, arranged parallel to the shaft 6 and disposed at equal distances apart, and suitably connected by intermediate rings 18, and end rings 19, and said latter rings are in turn secured to the 110

trunnions 20^a. Intermediate the end rings 19 the bars 17 of the cage are mounted on a supporting frame 19^a that is journaled on the shaft 6. (See Fig. 2^a). The trunnions 5 20^a are journaled to rotate on the shaft 6 at either end of the casing 1, in the trunnion bearings 20, and a pulley 21 is secured to one of said trunnions for rotating the cage 10 at a speed commensurate with the speed of the abrading cylinder, in the delinting operation.

The abrading cylinder is rotated through the medium of the pulley 22 secured at one end of the shaft 6, as illustrated in Fig. 1.

15 An agitating means is carried by the cage and consists of a series of pins or fingers 23 mounted on each cage bar 17, and are disposed inwardly, each annular series fitting between each pair of the corrugations of the abrasive cylinder, or immediately around the abrasive shoulders 5. With this arrangement of agitating members and abrasive shoulders, the seeds are caused to rub against the abrasive wheels on both sides of the corrugations 20 4 and against the cylindrical surfaces or annular shoulders 5, *i.e.*, the seed is forced to the extreme depth of channels formed by the abrading surfaces. And there is the further advantage that with having the agitating 25 pins 23 arranged at such intervals, the mass of seed is in a given time subjected to a greater working action by the abrasive wheels than would be the case if but one series of agitating pins were used.

30 35 From the foregoing it will be obvious that the construction is simple and not liable to easily get out of repair; and further that the saw cylinder is relieved, in a great measure, of its usual work, and as a result does 40 not require to be sharpened at close intervals.

It is obvious that various other modifications might be made in the herein described constructions without departing from the 45 spirit of my invention.

I claim:

1. In an abrasive cylinder for linters, the combination of a shaft; co-axially assembled bushings mounted on the shaft and having 50 annular channels; co-axially assembled abrasive cylinder sections mounted on said bushings; and an adhesive filling within said channels and securing the respective pairs of bushings and cylinder sections; substantially 55 as described.

2. In an abrasive cylinder for linters, the combination of a shaft; co-axially assembled bushings mounted on the shaft; co-axially assembled abrasive cylinder sections mounted 60 ed on said bushings; said bushings having

annular channels, and portions projecting into their respective abrasive cylinder sections to prevent relative movement therebetween; and adhesive fillings within said channels and securing said bushings and 65 cylinder sections; substantially as described.

3. In an abrasive cylinder for linters, the combination of a shaft; co-axially assembled bushings mounted on the shaft; said bushings having annular channels; co-axially 70 assembled abrasive cylinder sections mounted on said bushings; adhesive fillings within said channels securing said bushings and cylinder sections; and dowel-pins securing said bushings in axial alinement; substan- 75 tially as described.

4. In an abrasive cylinder for linters, the combination of a shaft; co-axially assembled bushings mounted on the shaft; co-axially as- 80 sembed abrasive cylinder sections mounted on said bushings; said bushings having each an annular channel, and a pair of integral and oppositely projecting portions fitting within its respective cylinder section to prevent relative movement therebetween; and ad- 85hesive fillings within said channels securing said bushings and cylinder sections; substan- tially as described.

5. In an abrasive cylinder for linters, the combination of a shaft; co-axially assembled 90 bushings mounted on the shaft; co-axially assembed abrasive cylinder sections mounted on said bushings; said bushings having each annular end flanges, and a pair of in- 95 tegral and oppositely projecting portions fitting within its respective cylinder section to prevent relative movement therebetween; said end flanges and projecting portions forming annular channels; adhesive fillings within said channels securing said bushings 10 and cylinder sections; and dowel-pins securing said bushings in axial alinement; sub- stantially as described.

6. In an abrasive cylinder for linters, the combination of a rotatably mounted polygonal sided shaft; co-axially assembled bushings mounted on the shaft; co-axially assembed abrasive cylinder sections mounted on said bushings; securing means between said bushings and cylinder sections; and rein- 11 forcing rings embedded in said cylinder sections, respectively; substantially as de- scribed.

In testimony whereof, I affix my signature, in presence of two witnesses.

GEORGE L. BLANCHARD.
